WARE.

LOCOMOTIVE-BOILER FURNACE.

1,138,048.

Specification of Letters Patent.

Patented May 4, 1915.

Application filed December 18, 1911. Serial No. 666,336.

To all whom it may concern:

Be it known that I, CHARLES B. MOORE, a citizen of the United States, and a resident of the city of Evanston, county of Cook, and

5 State of Illinois, have invented certain new and useful Improvements in Locomotive-Boiler Furnaces, of which the following is a specification.

My invention relates to improvements in 10 locomotive boiler furnaces and has special reference to improvements in refractory baffles, barriers or walls commonly called arches, for the fireboxes of locomotive boilers.

15 The general objects of my invention are to provide a refractory arch for locomotive boilers equipped with a plurality of inclined arch tubes, of light weight and low cost; to provide an arch that can be easily and 20 quickly installed, and which shall find its support upon said tubes; to provide an arch which shall be composed of a plurality of brick members so interlocked with each other and wedged between the side sheets of the 25 firebox that the arch as a whole will be securely maintained in its proper position; to provide an arch which can readily and easily be repaired and parts of which can be readily removed without disturbing the rest of 30 the arch to afford easy access to the side sheets and the flue sheet for necessary repairs thereof.

A particular feature of my invention resides in an arch which, in a practical sense, 35 provides a plurality of gas mixing pockets or cavities in combination with deflecting walls or surfaces occupying planes disposed at various angles in the firebox which not only deflect the gases of combustion out of 40 the direct path from the grate to the flues, but also enhance the commingling and admixing of the various portions of the gaseous body, to the end that substantially perfect combustion is maintained in the firebox.

45 A further object of my invention is to provide an arch, as above outlined, which, while finding its support upon the inclined arch tubes, will present surfaces longitudinally inclined at angles variant from the inclination of the tubes, and an arch in which portions thereof will be raised above the plane of the tubes, to the end that the combustion space below the arch may be enlarged.

50 My invention consists in the various assemblages and combinations of elements by

which the above objects are obtained, together with others hereinafter appearing and all as hereinafter set forth and particularly pointed out in the claims.

My invention will be more readily understood by reference to the accompanying drawings, forming part of this specification, and in which:

Figure 1 is a longitudinal vertical sectional view of a locomotive boiler firebox 65 equipped with a refractory arch illustrating one embodiment of my invention and taken on the line 1—1 of Fig. 2; Fig. 2 is a horizontal longitudinal sectional view on the line 2—2 of Fig. 1; Fig. 3 is a vertical transverse sectional view on the line 3—3 of Fig. 1; Fig. 4 is a detail transverse sectional view on the line 4—4 of Fig. 1; and Figs. 5, 6, and 7 are perspective 70 views of some of the brick forms or patterns used in the construction of the arch.

75 It will at once be understood that while I have limited the illustration and description of my invention to so-called front arches, my invention is not thus limited as it 80 is capable of embodiment in arches of different details of construction and occupying various positions within the firebox.

85 So-called front arches are arranged or positioned between the grate and the flue sheet 85 for the purpose of deflecting the firebox gases to the rear of the firebox, not only to retain them in the firebox for a time sufficient to complete their combustion, but also for the purpose of distributing the heat of 90 combustion over the entire inner surface of the firebox and especially throughout the whole length of the crown sheet. These arches usually occupy an inclined position close to or abutting the flue sheet and when 95 installed in fireboxes equipped with circulating or arch tubes they find their support upon these tubes. When the arch is laid flat upon these tubes it sometimes occurs on account of the low position of the tubes that 100 the space beneath the arch is too contracted for the best combustion effects to be attained. One of the particular features of 105 my invention resides in the means which I employ for raising a portion of the arch to increase this otherwise contracted space.

The locomotive boiler firebox, as illustrated, comprises a flue sheet 2, side sheets 3, 3, a crown sheet 4 and a rear sheet 5. The box itself is positioned within the shell 6 110

of the locomotive boiler and is provided with a grate 7 at its lower end. Flues 8 lead forward from the flue sheet, and the rear sheet is provided with a fuel door or opening 9. As illustrated, the firebox is equipped with a plurality of arch tubes 10 the same extending from the lower portion of the flue sheet rearwardly and upwardly to the rear sheet and serving to increase the circulation 5 of water between the front and rear water legs of the boiler. These tubes also serve as a foundation upon which I build my arch.

I preferably build my arches of a plurality of individual brick members, as large as 15 may be conveniently passed through the fuel door 9, and yet small enough or light enough to be handled and positioned with ease.

The embodiment of my invention illustrated in the drawings comprises a plurality 20 of longitudinally arranged sections or portions, viz., a middle or roof portion 11, two intermediate or supporting sections 12 and two side or locking sections 13, and each of 25 these sections includes a plurality of individual bricks. In the form shown, I raise the middle section above the other sections and incline it longitudinally in the firebox at an angle different from the inclination of the tubes 10. While this middle section 30 might be arranged above and parallel with the tubes 10, or inclined in either direction relatively thereto, I have found that when it is inclined, as shown in the drawings, with its lower end more distant from the 35 tubes, the best results are obtained in the fireboxes to which this form of arch is adapted. The intermediate or supporting sections 12 of the arch lie flat upon the tubes 10 and are supported thereby, thus 40 forming a lateral portion of the arch at each side of the middle portion and which is inclined longitudinally in the firebox at the same angle as the tubes 10. Locking sections 13 are arranged between intermediate 45 sections 12 and the side sheets 3 and are inclined upwardly against the side sheets. In a sense they serve as wedges between the main portion of the arch and the side sheets of the box to firmly maintain or lock the arch 50 against lateral movement in the firebox. As stated, these various sections are each made up of a plurality of individual bricks *a*, *b* and *c*, respectively, which, when assembled in place to form the arch, also form a plurality 55 of transverse rows 14 which are individually locked between the side sheets of the firebox.

The firebox, as illustrated, is equipped 60 with four arch tubes 10 arranged in two pairs, one at each side of the box, that is, the space or span between pairs of tubes is greater than the space between the individual tubes of each pair. The outer tubes are also arranged comparatively close to the 65 side sheets of the firebox. This arrangement

of tubes is particularly adapted for use with arches embodying my invention for the reason that the middle or raised portion of the arch can be made of greater extent than where the tubes are evenly spaced across the 70 firebox. Each of the spans or rows 14 consists of one of the middle or roof bricks *a*, two of the intermediate or supporting bricks *b*, and two of the end or locking bricks *c*. All of these bricks, panels or slabs are so 75 formed upon their meeting or abutting ends that the completed row is self-locked between the side sheets of the firebox, and each individual brick thereof is firmly locked transversely in its proper position. The 80 supporting bricks *b*, as clearly shown in Figs. 4 and 7, are L-shaped, transversely of the firebox, in section, having a long leg *b*' and a short leg *b*². Each of these bricks is arranged with its long leg spanning and 85 resting upon a pair of tubes 10 and its short leg upstanding at its inner end in position to receive the middle or roof brick *a*. The outer ends of the bricks *b*, and the inner 90 ends of the locking bricks *c*, are each cut 95 away to form an overlapping joint between them, the supporting brick having a lower projecting tongue or shelf *b*³ and the locking brick *c* being cut away on its lower side to form an upper tongue or flange *c*' adapted to rest upon said shelf *b*³. The bricks *c* are outwardly and upwardly inclined 100 against the side sheets and are tapered toward their outer ends both to reduce their weight and to reduce the area of the side sheet which is covered by the abutting end 105 of these bricks. The roof or middle brick *a* is provided with end flanges *a*' adapted to rest upon the upper ends of the legs *b*² of the supporting bricks. These bricks also project 110 downwardly between the supporting bricks thereby forming overlapped joints between the supporting bricks and the roof bricks and providing abutments by means of which the intermediate bricks are spaced apart. 115 The roof bricks *a* are provided on their under sides with large cavities *a*² which not only lighten the bricks *a* but also provide the roof of the arch with a plurality of shallow, gas-mixing cavities or pockets. As clearly shown in Fig. 1, the shorter legs *b*² of the intermediate bricks are properly proportioned to give the middle section 11 of the arch its desired inclination. As shown in said figures, the legs *b*² of the bricks *b*, 120 which are closer to the flue sheet, are longer than those of the bricks which are more distant from the flue sheet, thus relatively raising the forward end of the middle section 11 a greater distance from the tubes, adjacent 125 to the flue sheet.

In building my arches, I first place a pair of the intermediate bricks *b* in position upon the tubes 10 adjacent to the flue sheet. I sometimes provide this first pair of bricks 130

with projections b^4 adapted to abut the flue sheet and space these bricks therefrom. Upon these bricks I place one of the middle bricks a which not only closes the space between the bricks b but also serves to space these bricks apart. I complete the first row 14 of the arch by placing a pair of the end bricks c in position between the outer ends of the bricks b and the side sheets 3. These 10 bricks c are longer than the space between the ends of the bricks b and the side sheets, and hence occupy upwardly inclined positions wedgingly locking the main portion of the arch transversely in the firebox. 15 Thereafter I place a second transverse row of bricks in position upon the tubes and resting against the first row, the arch being completed by additional rows sufficient in number to produce an arch of the desired 20 length and height, which height is determined by that which will produce the best results in the firebox being equipped.

It will now be seen that arches can be built embodying my invention, with a minimum expenditure of labor and time, as they are built of a number of individual bricks which can be quickly placed in position; that they are capable of such modification as may be necessary to produce the most economical 30 results in fuel consumption when considered in relation to the boiler being equipped; that these arches are capable of being easily repaired; that they are in a sense flexible, as their overlapping joints prevent them from 35 becoming solidified into a rigid mass, and that portions of the arch can be easily removed when it is necessary to repair the stay bolts or the flues.

It will be readily understood that my invention is capable of embodiment in various 40 structures and forms without departing from the spirit of the invention, and I therefore do not limit my invention to the specific structures or combinations of elements here- 45 in shown and described.

Having thus described my invention, I claim as new and desire to secure by Letters Patent:

1. A locomotive boiler firebox containing 50 a group of arch tubes arranged substantially in a single inclined plane, in combination with a refractory front arch supported upon said tubes and comprising a central longitudinal section or portion supported above 55 said tubes and at less pitch than the tubes, and side sections resting upon the tubes and supporting said middle section in position, said intermediate section having positive stop shoulders serving to space the side sections, 60 the said central and side sections being locked between the side sheets of the firebox by wedge bricks extending between the side sections and the side sheets.

2. A refractory front arch for locomotive 65 boiler furnaces comprising an arch body

extending from side to side of the firebox and composed of a plurality of longitudinal rows of refractory bricks, one of which rows is centrally disposed in the firebox, and rows on either side thereof having upwardly 70 extending portions having tops disposed longitudinally at an angle to the tubes and supporting said middle section at a longitudinal angle to the tubes.

3. A refractory front arch for locomotive 75 boiler furnaces having a central longitudinal comparatively deep and wide channel in its underside of greater depth at the lower end than at the upper end, the top of said channel having a plurality of gas mixing pockets 80 or cavities, substantially as described.

4. A refractory front arch for locomotive boiler furnaces having a group of arch tubes, comprising longitudinally arranged side sections, each of which rests upon two 85 tubes and having upstanding flanges or walls on their opposed edges, the tops of said walls being inclined longitudinally to the plane of said tubes, and a middle section spanning said walls closing the spaces there- 90 between and having abutment shoulders engaging the side sections and holding them in proper spaced relation.

5. A refractory front arch for locomotive boiler furnaces having a parallel group of 95 arch tubes, comprising longitudinally arranged side sections having thin upstanding walls at their opposed edges, said walls rising higher above the tubes at the front than at the rear end of the arch, and a central 100 roof section resting on said walls, closing the opening therebetween and having abutment shoulders serving to hold the side sections in proper spaced relation.

6. A locomotive boiler firebox containing 105 a group of arch tubes arranged substantially in a single inclined plane, in combination with a refractory front arch supported upon said tubes and comprising a central longitudinal section or portion sup- 110 ported above and at less pitch than the tubes, and side sections resting upon the tubes and supporting said middle section in position, and wedge bricks extending between said side sections and the side sheets of the fire- 115 box.

7. In a locomotive front arch, two parallel refractory side bricks having upstanding portions upon their opposed ends in combination with a refractory middle brick rest- 120 ing upon and presenting shouldered ends to said portions.

8. In a locomotive front arch, two parallel refractory side bricks having upstanding inclined portions upon their opposed ends 125 in combination with a refractory middle brick resting upon and presenting shouldered ends to said portions.

9. In a locomotive front arch, two parallel refractory side bricks having upstanding 130

portions upon their opposed ends and having shouldered outer ends in combination with a refractory middle brick resting upon and presenting shouldered ends to said portions, and side sheets engaging refractory bricks having inner ends formed to fit the shouldered outer ends of respective side bricks.

10. In a locomotive boiler firebox, the side sheets and the inclined water-circulating arch-tubes, in combination with two longitudinal rows of refractory bricks resting upon said tubes, other longitudinal rows of refractory bricks resting thereon and against 15 respective side sheets, the bricks of the first mentioned rows having upstanding portions upon their inner ends, and a central longitudinal row of refractory bricks supported by and shouldered upon said portions.
20. 11. In a locomotive boiler firebox, the side sheets and the inclined water-circulating arch-tubes, in combination with two longitudinal rows of refractory bricks resting

upon said tubes and together presenting parallel upstanding portions having top surfaces of less pitch than said tubes, and a central longitudinal row of refractory bricks supported by said upstanding portions of said rows.

12. A locomotive boiler firebox containing 25 two pairs of inclined water-circulating arch-tubes, in combination with a row of refractory bricks upon each pair of tubes, said bricks having upstanding portions upon their inner ends and a middle row of refractory bricks having shouldered ends resting upon said portions and spacing said rows apart.

In testimony whereof, I have hereunto set my hand this 5th day of December, 1911, 30 in the presence of two subscribing witnesses.

CHARLES B. MOORE.
